UNITED STATES PATENT OFFICE.

WALTER R. SPRINGER, OF YOUNGSTOWN, OHIO.

TIE.

1,099,826.

Specification of Letters Patent.

Patented June 9, 1914.

Application filed January 20, 1914. Serial No. 813,259.

To all whom it may concern:

Be it known that I, WALTER R. SPRINGER, a citizen of the United States, residing at Youngstown, in the county of Mahoning and State of Ohio, have invented new and useful Improvements in Ties, of which the following is a specification.

The present invention relates to ties for railway rails, and resides in the construction, combination and arrangement of parts set forth in the following specification and falling within the scope of the appended claims.

In the drawings: Figure 1 is a perspective view illustrating a tie constructed in accordance with the present invention showing rails supported thereon, Fig. 2 is an enlarged detail perspective view looking toward one end of the tie and illustrating the manner in which the jointed ends of two railway rails are sustained upon the tie, Fig. 3 is a similar perspective view of the tie, the rail seat or chair being removed, Fig. 4 is a perspective view of the rail seat, Fig. 5 is a plan of the rail seat before the same has been shaped, Fig. 6 is a perspective view of the lock block, Fig. 7 is a similar view of the wedge-key, Fig. 8 is a view of the blank from which the tie proper is formed, Fig. 9 is a bottom plan view of the tie, Fig. 10 is a central transverse sectional view taken through the rail seat and tie, and Fig. 11 is a longitudinal sectional view taken through the rail seat and tie as well as through the rail seat upon the tie and the locking block and the wedge-key.

In the drawings, like reference characters designate similar parts throughout the several views.

Referring now to the drawings in detail, the numeral 1 designates my improved tie complete. The tie embodies an outer shell which includes a horizontally straight top 2, angular sides 3 having a bottom 4. The shell is formed from a single strip of metal, as disclosed in the figure illustrating the blank of the same, and the inturned lower portions of the side which form the base 4, are centrally provided each, upon its longitudinal edge, with a rectangular opening 5, the said openings registering when the shell is formed to provide the body for the tie, and the registering openings are provided to permit of the insertion of the plastic body to the interior of the shell, or to permit of the

entrance of the dirt from the roadbed to 55 within the shell. The open ends also provide means whereby a plastic material may be inserted within the shell or whereby dirt from the roadbed may be inserted and tamped within the shell. It will be noted 60 that the bottom 4 is of a greater width than the top 2 so the sides 3 slope from the said top to the bottom. This arrangement is desirable and advantageous for the reason that the roadbed, tamped against the inclined 65 sides, will prevent a longitudinal movement or tilting of the tie.

The top 2, at a suitable distance from the ends of the tie, is provided with transverse cut-away portions or openings 5^a which 70 merge into the sides of the tie at the upper portion thereof, the edges provided by the said openings in the sides being cut longitudinally in opposite directions, as indicated by the numerals 6 and 7 respectively, the 75 lower edge of the cut-away portion 6 being disposed below the lower edge of the portion 7, but the edge 7 terminates in a vertical shoulder 8, the lower portion of which being slotted to provide a horizontally straight 80 wall or edge 9, the same terminating beyond the outer longitudinal edge provided by the cut-away portion 5^a in a downwardly extending shoulder 10. This shoulder 10 terminates in a longitudinally extending edge 85 11, the said edge in turn terminating with a vertically disposed wall or shoulder 12 which communicates and forms the terminal of the wall or edge 6.

Arranged flush with the opposite walls or 90 edges 11 is a transversely arranged I-beam 13, the said I-beam having its ends beveled and secured to the bottom 4 of the shell, and the said I-beam 13, is positioned to be arranged directly below and centrally of the 95 rails, which are adapted to be secured to the tie in a manner which will hereinafter be fully set forth.

The rail seat is designated by the numeral 14. This seat is, as disclosed by the diagram, also constructed from a single piece of suitable metal, and includes a base of two dimensions, one indicated by the numeral 15 and the second by the numeral 16. The base 13 is elevated above the base 15 a distance 100 105 equaling the height of the shoulders 10 in the sides of the rail, and the base 16 is of a length equating the width of the walls 9,

while the length of the base 15 corresponds with the width of the walls or edges 11 in the said sides of the rail. The end of the base 15 is upset as at 16^a, the height of the upset portion corresponding with that of the vertical edges 12 in the sides, and the portion 16^a is bent horizontally, as at 17, and the said portion 17 extends inwardly over the base 15 from the upset portion 16^a a distance equaling the length of the walls or edges 6 of the sides, the said portion 17 being bent outwardly, as at 18, to fill the space provided between the end walls or vertical edges of the portions 6 and the transverse walls 7 provided by the cut-away portion 5^a. The elevated base 16 has its end upset, as at 19, and from thence continued over its base, as indicated by the numeral 20, the said portions 19 and 20 filling the space between the shoulders 8 and the edge or wall which terminates in the shoulder from which the wall 9 extends. The portion 20 is bent upwardly, as at 21, to engage with the shoulders 8 and from thence bent inwardly, as at 22, to underlie the upper portions or edges of the side which provide the shoulder 8, and the portion 22 terminates in an upset lip 23 which closes the edges provided by the opening 5^a opposite to that closed by the portion 18.

The portions above set forth correspond in width with that of the tie, but the base portions 15 and 16 are extended and said extensions bent downwardly to provide side members or flanges 24 and 25 respectively, the said flanges having openings for the reception of securing elements, whereby the rail seats are secured to the sides of the tie. The base portions 16 serve as seats for rails R, and in order to sustain the said rails upon their seats, I provide lock blocks 26. These blocks embody each a base 27 which rests upon the base 15 of each of the rail seats, the said base having, what I will term, its inner face provided with a longitudinally extending groove 28, the lower wall of which being horizontally straight and being elevated from the bottom of the block a distance equaling the shoulder or riser between the portions 15 and 16 of the rail seat 14, so that the said wall will receive the base flange upon one of the sides of the rails R. The upper wall 29 provided by the slot 28 is shaped to agree with the cross sectional shape of the rail and to engage with the outer longitudinal edge of the said rail, and the angular wall 29 is intersected by a vertical shoulder 30 from which extends a lateral straight wall 31 that terminates in the vertically straight inner face 32 of the block. The upper face of the block to the rear of its rail engaging portion is provided at its outer corner with a longitudinally extending depressed portion 33, the upper wall of said depression being elevated above the

lower wall or block a distance equaling the distance between the base 15 and the overlying portion 17 of the rail seat, while the longitudinal edge of the wall 33 and of the block proper, is arranged angularly with respect to the vertically straight sides or ends of the block, the said inclined wall or end being indicated by the numeral 34.

The numeral 35 designates a wedge key which is adapted to be seated between the upset portion 16 of the rail chair and the longitudinal edge 34 of each of the blocks 27, the said key having one of its ends formed with an elongated slot 35 for the reception of the removable securing element, 80 preferably in the nature of a cotter pin 36.

If desired, one of the edges of the base portion 4 may overlap the second edge and the said edges may be secured together through the medium of bolts, rivets or similar securing devices, and also to facilitate the handling of the tie, especially in moving the same laterally of the roadbed to arrange one of the ties in proper relation to the remaining ties, the top 2, adjacent the ends thereof being preferably formed with openings 50 for the reception of either the pointed or hooked end of a crow.

The arrangement of the seat upon the tie is such that only the outer longitudinal edges 95 of the base flanges of the rail are engaged by the portions 9 and the overlying wall 20 of the seat proper and by the overlying angular wall 29 of the block, a space being left between the tie, the seat and the lock 100 block for the reception of angular fish plates, as shown in the drawings, and also I have found it desirable to provide simple means for holding the block against lateral movement when and after the wedge key is applied, and to accomplish this I provide the seat 15 with a longitudinally extending slot or opening 51, and the underface of the block 27 with a depending lug 52 which is adapted to be received within the seat opening when the block is positioned upon the seat. The lug 52 is, of course, of a width less than the length of the slot to permit of the longitudinal movement of the wedge block with relation to the rail seat.

A tie constructed in accordance with my invention when properly fitted to the rails will positively prevent the spreading thereof. A perfect joint is also made within the tie by fish plates as in the usual manner, giving 120 greater strength by being reinforced by the tie proper. It is also quickly removed by simply removing the split key from wedge. To obtain best results this tie should be placed alternately end for end. It will at all times keep track to gage and will give freedom and flexibility, same as wooden ties. This tie may be worked in a roadbed constructed of wooden ties as a non-spreading feature, using four metallic ties per rail 130

length, or track may be wholly constructed of this type of tie. It may also be used on bridges with no fear of fire danger and will add strength to same, and will be found to work on a curve with same good results. Switch ties may be made with few additional changes. This tie is constructed of either cast or pressed steel, being hollow and may be reinforced with concrete if necessary. It can be made to any dimensions, according to individual road masters' theory. When made of pressed steel, old material, such as plates from boilers, tenders, steel coaches and cars can be used. When the tie is no longer useful for track purposes, there still remains the scrap iron for revenue.

Having thus described the invention, what I claim is:

1. A rail tie including a metallic shell having open ends and having its top and sides cut adjacent its ends to provide openings in the said top and ends, a rail seat arranged within each of the openings, said seat having side flanges which are secured to the sides of the tie, a rail locking block for each of the seats, a wedge key for sustaining the locking block within its seat, and into frictional engagement with a rail upon the seat.
2. A rail tie including a metallic shell having open ends and having its top and sides cut to provide openings in the said top and sides, a rail seat arranged within the openings and engaging the walls provided thereby, said seat having a stepped base, the sides of said base having flanges which are secured to the sides of the tie, the elevated portion of the base adapted to receive a rail, a rail locking block having its base portion upon the lower stepped portion of the base, and a key arranged between the outer edge of the block and one of the vertical walls of the seat for forcing the block into frictional engagement with the rail.
3. A rail tie including a metallic shell having open ends and having its top and sides cut to provide openings in the said top and sides, a rail seat arranged within the openings and engaging the walls provided thereby, said seat having a stepped base, the sides of the said base having flanges which are secured to the sides of the tie, the elevated portion of the base adapted to receive a rail, a rail locking block having its base portion upon the lower stepped portion of the base, a key arranged between the outer edge of the block and one of the vertical walls of the seat for forcing the block into frictional engagement with the rail, and means arranged between the block and seat for sustaining the block against lateral movement.

4. A tie including a metallic shell having a base of a greater width than its top and its sides inclined from its base to its top, the

top and sides being cut to provide openings, a rail seat shaped to correspond with the edges of the rail provided by the openings and supported upon the said edges, the seat having side flanges which are secured to the sides of the rail, a rail locking block loosely positioned upon each of the seats, means for sustaining the locking block against lateral movement upon the seats, and a wedge key engaging between one of the walls of the seat and one of the edges of the block for moving the block longitudinally to engage with the rail upon the seat and for sustaining the block in such engagement.

5. A rail tie including a metallic shell which has its top cut and its sides notched in opposite directions from the edges provided by the cut top, a rail seat having its ends shaped to correspond with the notched sides and the cut top and resting upon the edges formed by the said cut and notches, means for securing the seat upon the tie, a brace connected with the sides of the tie and engaging beneath the portion of the seat upon which a rail rests, a rail locking block having one of its faces notched to receive one of the base flanges of the rail, arranged upon the seat, the opposite end of said block being recessed to engage within the portion of the seat disposed within the notch at this portion of the tie, a wedge key for forcing the block into engagement with the rail, and means for sustaining the wedge key upon the tie.

6. A rail tie formed from a flat sheet of metal to provide a horizontally straight top, outwardly inclined sides having their ends inturned and horizontally straight and the edges of said ends meeting to provide a base of a greater width than the top, the top, adjacent its ends being formed with openings, the sides being notched longitudinally in opposite directions and communicating with the openings, the lower edges of the notched portions being raised one above the other, rail seats also formed from a single strip of metal bent to correspond with the edges provided by the notches and the transverse cuts of the top and having side flanges which are secured to the sides of the tie, the rear portion of the base of each of the seats having walls corresponding to the cross sectional shape of a rail and a portion of the web of the rail as well as that of an angular fish plate for the rail, the said elevated rail receiving portion of the base of the seat resting upon an I-beam that is secured to the sides of the tie, the second floor of the chair having a longitudinal slot, a lock block having one of its faces shaped to engage the shoulder between the two base portions of the chair and being slotted to provide a rail base and chair receiving groove, the said block having its upper face at its opposite corners depressed to be received with

in the portion of the chair filling the notch at this portion of the chair, the lower longitudinal edge of said notched portion being beveled, the underface of the chair having a lug which is received within the slot in the chair, a wedge key passing between the beveled edge of the chair and one of the vertical walls provided by the seat, said

wedge key having an elongated opening, and a cotter pin passing through the opening.

In testimony whereof I affix my signature in presence of two witnesses.

WALTER R. SPRINGER.
